UNITED STATES PATENT OFFICE.

AUGUSTUS SMITH, OF ROSELLE, NEW JERSEY, ASSIGNOR TO BERGEN POINT IRON WORKS, OF BAYONNE, NEW JERSEY, A CORPORATION OF NEW JERSEY.

TELESCOPIC CHUTE.

1,181,933.

Specification of Letters Patent.

Patented May 2, 1916.

Application filed March 24, 1914. Serial No. 826,909.

To all whom it may concern:

Be it known that I, AUGUSTUS SMITH, a citizen of the United States of America, and residing at Roselle, in the county of Union 5 and State of New Jersey, have invented a certain new and useful Improvement in Telescopic Chutes, of which the following is a specification.

The present invention relates to chutes 10 and particularly to an improvement in apparatus for operating telescopic chutes so that they can be conveniently lengthened, shortened and swung in vertical and horizontal planes.

15 In the accompanying drawings, Figures 1 to 4 are side elevations, more or less diagrammatic, and illustrating four different embodiments of my invention.

In Fig. 1 I have shown a chute with single 20 telescopic portion suspended from an inclined boom, the vertical angle of which is controlled by means of a topping up rope. Fig. 2 shows a similar telescopic chute and boom but, in this case, the vertical angle of 25 the boom is controlled by a strut which takes the place of the topping up rope in Fig. 1. Fig. 3 shows the chute with two telescopic portions and a small auxiliary boom hinged on the axis of the large inclined boom together with topping up rope. Fig. 4 shows a 30 different method of reeving the chute suspension ropes and a different method of getting the parallel motion secured in the preceding arrangements.

35 In general the apparatus consists of a pivoted inclined chute with one or more telescopic or extension pieces, the extension pieces being supported by ropes of fixed 40 length to rolling or sliding trolleys which operate on an inclined boom. The centers and lengths of the different members are taken so that the boom and chute are, at all 45 times, practically parallel to each other so that, to adjust the overall length of the chute, it is only necessary to move the rolling or sliding trolley on its boom and the telescopic portion will then slide in or out 50 without changing the vertical angle on which the chute is operating. When it is desired to change the angle of operation of the chute, the vertical angle of the boom is correspondingly changed and the different telescopic portions of the chute are held in a straight line at all times, due to the fact that 55 the boom is at all times parallel to the chute.

Referring to the arrangement shown in Fig. 1, the main portion of the chute C is pivoted at P about which center it is free to rotate. The telescopic portion of the chute E is suspended by the two suspension rods 60 or ropes S and S¹ from the trolley T which runs on the boom B on the rollers R and R¹. The boom B is hinged at the pin H, vertically alined with the pivot P, and its vertical angular position is adjusted by the topping 65 up rope U controlled by the drum D. The in and out position of the trolley T in respect to the boom B is controlled by a trolley rope A leading to a drum B¹. The vertical angular position of the chute may be changed by 70 raising or lowering the boom B by means of the topping up rope U. The chute will then revolve about the hinge P and the telescopic portion E will not change its position relative to the main portion C so that the total 75 length of the chute will remain the same and the telescopic portion E will be held parallel to the main portion C. When the chute is standing at any inclined position it may be telescoped in or out by adjusting the trolley 80 rope A, thus rolling the trolley T on the boom B and causing the telescopic portion of the chute E to slide in or out relative to the main portion of the chute C without changing 85 the vertical angle of the latter.

In the construction shown in Fig. 2, the vertical angle of the boom B is adjusted by means of a strut F pivoted to the boom B at J and having at its inner end a roller K rolling on a vertical track L. The position of the roller K on the track L is controlled by a pull down rope U¹ which winds on the drum D¹. When the strut F is pulled down toward the drum D¹ it shoves boom B toward its outboard position. The operation 90 of the telescopic chute E and trolley T is the same in this case as described 95 above for Fig. 1.

In the construction shown in Fig. 3, an intermediate telescopic chute I is introduced between the main chute C and the end portion of the telescopic chute E. This intermediate chute I is suspended by means of a suspension rod or rope M from a trolley N which also runs on the boom B. The 100 length of the suspension rod M is the same as the suspension rods S and S¹ supporting the chute E so that the intermediate telescopic chute I, the end telescopic chute E and the main chute C are maintained at all 110

times parallel. Obviously the one telescopic intermediate chute I could be increased to any reasonable number to suit varying conditions and these intermediate chutes could also be used in the constructions illustrated in Figs. 1, 2 and 4.

Referring again to the apparatus shown in Fig. 1, when this apparatus is housed in, *i. e.*, when the chute C and boom B are hanging nearly vertical, it is hard to pull the boom B out on account of the poor lead of the topping up rope U. To meet this difficulty, which is also present in the construction shown in Fig. 3, an auxiliary boom O (Fig. 3) may be introduced. When the boom B is hanging nearly vertical this auxiliary boom O is also nearly vertical, but when the topping up rope U is taken in, the auxiliary boom swings out without imparting motion to the boom B until it has reached a position where its limit rope Q gets taut, at which point the boom B and, therefore, the chute, starts to rise and this device gives a good lead to the topping up rope U.

In the foregoing Figs. 1, 2 and 3, the boom and chute are at all times practically parallel to each other so that the main chute and the telescopic portions are maintained parallel in all positions. Fig. 4 shows another method by which the parallelism of the main chute and the telescopic portions can be maintained even when the boom is not parallel to the chute. In this case, instead of the telescopic chute suspension ropes being made fast directly to the trolleys as in the former cases, they lead over sheaves V on the trolley T¹, N¹, and are then made fast at the end of the boom B. In the position shown in Fig. 4 the boom B is horizontal and the chute is standing at 45 degrees. When a given motion is imparted to the trolleys T in the horizontal direction, a corresponding vertical motion is given to the suspension ropes S, S¹, M¹. Thus, if the trolleys T¹, N¹ are rolled in one foot, the suspension ropes S, S¹, M¹ will also move in one foot inasmuch as they always hang vertically, and, at the same time they will be simultaneously shortened up in length one foot. The operation of the telescopic chutes consequently will be similar to that described above for Figs. 1, 2 and 3.

The particular advantage of the construction of this apparatus is that the length and vertical angle of the telescopic chute can, at all positions, be easily and simply controlled with little or no possibility of the chutes jamming one on the other as is usually the case with other forms of apparatus.

I claim as my invention:—

1. In apparatus of the character described, a chute having a telescopic extension section,

a pivotal support for the upper end of the chute, an overhead support for holding said chute in normally inclined operating position, and means traveling longitudinally on said support for extending and retracting 70 said extension section of the chute in inclined position.

2. In apparatus of the character described, a chute having a telescopic extension section, a pivotal support for the upper end of 75 the chute, an overhead support for holding said chute in normally inclined operating position, and means traveling longitudinally on said support for extending and retracting said extension section of the chute in inclined position, in telescopic parallelism to the pivoted top section thereof.

3. In apparatus of the character described, a chute having a telescopic extension section, a pivotal support for the upper end of the 85 chute, an overhead pivoted boom for raising said chute to normally inclined operating position, and means traveling longitudinally on said support for extending and retracting said extension section in inclined 90 position.

4. In apparatus of the character described, a chute having a telescopic extension section, a pivotal support for the upper end of the chute, an overhead pivoted boom for raising 95 said chute to normally inclined operating position, and means traveling longitudinally on said support for extending and retracting said extension section in inclined 100 position, in telescopic parallelism to the pivoted top section thereof.

5. In apparatus of the character described, a chute having a telescopic extension section, a pivotal support for the upper end of the chute, an overhead boom pivoted on an 105 axis vertically aligned with that of the chute, and means traveling longitudinally on said boom for extending and retracting the extension section of the chute in inclined position. 110

6. In apparatus of the character described, a chute having a telescopic extension section, a pivotal support for the upper end of the chute, an overhead boom pivoted on an 115 axis vertically aligned with that of the chute, and means traveling longitudinally on said boom for extending and retracting the extension section of the chute in inclined position, in telescopic parallelism to the pivoted 120 top section thereof.

7. In apparatus of the character described, a chute having a telescopic extension section, a pivotal support for the upper end of the chute, an overhead support for holding said chute in normally inclined operating position, means traveling longitudinally on said support for extending and retracting said extension section of the chute in inclined 125 position, and a supporting rope of fixed length operatively connected to said traveling 130

means and to said extension section for supporting the latter.

8. In apparatus of the character described, a chute having a telescopic extension section, 5 a pivotal support for the upper end of the chute, an overhead support for holding said chute in normally inclined operating position, means traveling longitudinally on said support for extending and retracting said extension section of the chute in inclined position, and a supporting rope of fixed length operatively connected to said traveling means and to said extension section for supporting the latter, in telescopic parallelism 10 to the pivoted upper section of the chute.

9. In apparatus of the character described, a pivoted telescopic chute, an overhead supporting boom, trolleys traveling longitudinally on said boom and connections therefrom to the telescopic sections of the chute, said connections being such as to maintain the chute sections parallel in either extended 20 or retracted position, together with a top-

ping up rope for lifting and lowering the boom independent of the longitudinal movement of the trolleys thereon, substantially as described. 25

10. In apparatus of the character described, a pivoted telescopic chute, an overhead supporting boom, trolleys running on 30 said boom and connections therefrom to the telescopic sections of the chute, a topping up rope for lifting and lowering the boom and an auxiliary boom to which said topping up rope is directly connected, said auxiliary 35 boom having a slack connection to the outer end of the main boom, for the purpose described.

In testimony whereof I have signed my name to this specification, in the presence of 40 two subscribing witnesses.

AUGUSTUS SMITH.
